UNITED STATES PATENT OFFICE.

ALEXANDER MURRAY, OF NOTTINGHAM, ENGLAND, ASSIGNOR OF ONE-HALF
TO JOHN TURNEY, OF SAME PLACE.

MACHINE FOR PRESSING HOSIERY, &c.

SPECIFICATION forming part of Letters Patent No. 508,333, dated November 7, 1893.

Application filed March 11, 1893. Serial No. 465,659. (No model.)

To all whom it may concern:

Be it known that I, ALEXANDER MURRAY, a subject of the Queen of Great Britain, residing at Old Basford, in the town and county of Nottingham, England, have invented certain new and useful Improvements in Machines for Pressing Hosiery and other Goods and Fabrics, of which the following is a specification.

10 The invention relates to that class of press having a hollow bottom bed and a hollow top bed, both being heated by steam. Heretofore, in such class of press, either the top or bottom bed has been a fixture, as far as lateral movement is concerned and the top or bottom bed has been capable of only a short rising and falling motion obtained by a screw and fly arms, which construction has rendered it difficult to arrange goods on the bottom bed unless such goods were mounted on boards.

Now, according to the present invention, a hollow top bed is employed, which is mounted and operated as before, but instead of employing a fixed bottom bed, the bottom bed is mounted on suitable guides and supports so as to enable the same to be moved outward clear of the top bed when required to arrange goods thereon for pressing and to remove the goods after they have been pressed, 30 and to enable such bottom bed to be run in under the top bed for the pressing to be effected. Suitable gearing is provided so that the bottom bed may be moved to and fro as required either by hand or by power, and the 35 steam pipes connected to the same are either jointed or made to slide so as to enable them to follow the motions of the bottom bed.

The invention is represented in the accompanying drawings, in side elevation in Figure 40 1 and in plan in Fig. 2.

In both figures like parts are indicated by similar letters of reference.

45 *a* represents the top bed, which is acted upon by a screw *b* and fly arms *b'* to force it downward toward the bottom bed and is raised by said screw aided by springs *c' c'* arranged around guide rods *c c*, two of which are shown at each end of the bed *a*. These guide rods *c c* are fixed at their lower ends to bars *d'* 50 which are fixed one on each side of the machine to a standard *d²* of the frame *d*. The

upper ends of these guide rods *c c* fit into guide lugs *a' a'* formed on each end of the top bed *a*, and to the center of each bar *d'* is fixed the lower end of a rod *e*, which at its upper end carries the head or cross bar through which the screw *b* works. These rods *e e* also serve to guide the top bed *a* by passing between guide lugs *a² a²* at each end of the said top bed. The bottom bed *f* is provided with 60 descending bearing brackets or feet *f'*, which are supported on the axles *g'* of flanged wheels *g*, and these latter run on rails *d³* fixed to or forming part of the framing *d*. The bottom bed *f* has fixed to one end thereof bearing brackets *f²*, through which passes a shaft *h'* provided with toothed wheels *h*, and these latter mesh with toothed racks *d⁴ d⁴* fixed one on each side of the frame *d* by means of brackets *d⁵ d⁵*. The shaft *h'* has fitted thereto hand wheels *h²* 70 by which it can be rotated and thereby cause the bottom bed *f* to be run in under the top bed when the pressing is to be effected and to be moved outward clear of the top bed when it is required to arrange goods thereon 75 for pressing. The top bed *a* is formed hollow or with passages therein and it is connected by long bent pipes *i i* with the main steam pipes *j j* as usual to enable the same to be heated by steam and to be free to rise and 80 fall. The bottom bed *f* is also made hollow or with passages therein and it is connected by jointed pipes *k k* with branch pipes *j' j'* connected with the main steam pipes *j j*. By supporting the bottom bed *f* by brackets *f'* resting on the axles *g'* of the carrying rollers *g*, friction is obviated when moving the bottom bed *f* to and fro.

The machine as represented in the drawings is provided with hand driving gear, but if desired power driving gear may be employed.

If desired, in lieu of jointed steam pipes *k* connected to the bottom bed, straight pipes may be used passing through stuffing boxes attached to the bottom bed so as to slide 95 steam-tight in and out of the bottom bed *f* as the latter is moved to and fro.

By the aid of the present improvements considerable economy in labor is effected, the employment of press-boards can be dispensed 100 with and a uniform finish obtained which advantageously replaces the ordinary ironing

and by hydraulic pressing processes in respect to the general classes of goods in the trade.

As a modification the bottom bed may be 5 made to remain within the body of the press and the top bed to move in and out therefrom as above described for the bottom bed, in which case the top bed will be provided with supporting and traveling gear as will be well 10 understood.

Having fully described my invention, what I claim, and desire to secure by Letters Patent, is—

1. A press comprising interiorly heated top 15 and bottom beds, mechanism for moving one of the beds vertically, whereby the goods are pressed and released, and mechanism for moving one of the beds horizontally, whereby the bottom bed is exposed, when it is required to arrange the goods thereon, or to remove the goods therefrom and whereby the horizontally moving bed is placed in proper relation with the vertically moving bed for pressing; substantially as herein shown and 20 described.

2. A press comprising interiorly heated top and bottom beds, mechanism for moving one of the beds vertically, whereby the goods are pressed and released, and mechanism con- 25

sisting of a supporting and reciprocating carriage, and gear, whereby the bottom bed is exposed when it is required to arrange the goods thereon and to remove the goods therefrom, and whereby the horizontally moving bed is placed in proper relation with the vertically moving bed for pressing; substantially as herein shown and described.

3. A press comprising a heated top bed, screw and supporting springs by which vertical motion is imparted to the top bed, a reciprocating heated bottom bed provided with supporting wheels, the side rails on which the wheels run, and the toothed gearing and racks by which the reciprocating bed is operated, substantially as herein shown and described.

4. A press comprising a heated top bed, a traveling heated bottom bed, main pipes, and jointed pipes, whereby the bottom bed is connected with the main pipes; substantially as herein shown and described.

ALEXANDER MURRAY.
